DESIGN FOR A GLASS CREAM PITCHER OR ARTICLE OF SIMILAR NATURE

Ferdinand S. Barbiers, Lancaster, Ohio, assignor
to Anchor-Hocking Glass Corporation, Lan-
caster, Ohio, a corporation of Delaware

Application May 13, 1939, Serial No. 84,980

Term of patent 7 years

To all whom it may concern:

Be it known that I, Ferdinand S. Barbiers, a citizen of the United States of America, residing at Lancaster, in the county of Fairfield and State of Ohio, have invented a new, original, and ornamental Design for a Glass Cream Pitcher or Article of Similar Nature, of which the following is the specification, reference being had to the accompanying drawing, forming a part thereof.

Figure 1 is a side elevational view of a cream pitcher, showing my new design.

Figure 2 is a top plan view of the article.

Figure 3 is an end elevational view of the handle of the pitcher.

Figure 4 is a transverse sectional view taken along line 4—4 of Figure 3.

Figure 5 is a horizontal sectional view taken along line 5—5 of Figure 1.

I claim:

The ornamental design for a glass cream pitcher or article of similar nature, substantially as shown.

FERDINAND S. BARBIERS.
